(57) **CLAIM**

The ornamental design for a nonwoven fabric, as shown and described.

DESCRIPTION

FIG. 1 is front perspective view of a portion of a nonwoven fabric, embodying the new design;

FIG. 2 is a plan front view of the nonwoven fabric of FIG. 1;

FIG. 3 is a plan rear view of the nonwoven fabric of FIG. 1; and,

FIG. 4 is a cross-sectional view taken in the direction of line 4-4 of FIG. 2.

1 Claim, 4 Drawing Sheets
